UNITED STATES PATENT OFFICE.

GEORGE ANDREWS SMITH, OF SOUTH HILL, VIRGINIA.

BOX-SHOOK-EDGE-TRIMMING MECHANISM.

1,267,922.

Specification of Letters Patent. Patented May 28, 1918.

Application filed August 29, 1917. Serial No. 188,842.

To all whom it may concern:

Be it known that I, GEORGE A. SMITH, a citizen of the United States, residing at South Hill, in the county of Mecklenburg and State of Virginia, have invented a new and Improved Box-Shook-Edge-Trimming Mechanism, of which the following is a specification.

My present invention has particular reference to the manufacture of box shooks and particularly to shooks that are cut to the desired predetermined widths by planing machines in which the matcher or cutter heads are set to their operative position by the board being operated on, and which automatically sets the matcher or cutter head or heads to the desired predetermined position, or in other words, if a board say $3\frac{3}{8}$ " wide is passing to the shiftable cutter head, the latter is automatically set for edge trimming boards of that particular width and, when the boards are say 4" wide, the cutter head is correspondingly set.

In the process of edge trimming board lengths of standard widths, and which are cut up into shook lengths, one or both edges of the shook are at times defective, either by reason of bark edges or by irregular or knotty portions.

In the manufacture of certain kinds of boxes, those made up in standard sizes, and whose sides, ends, bottom and top members are made up from a combination of "shooks" of different widths, for example $3\frac{1}{2}$, $3\frac{1}{4}$, 4, $4\frac{1}{4}$ and $4\frac{1}{2}$ inches, more or less, mechanical nailers are utilized for framing up and nailing box sections and in the use of such mechanical nailers, it is necessary that the several box sections be positively uniform and free of knots to meet the requirements of such nailing machines, and by reason of the said requirements of mechanical nailers, it is necessary, when cutting up the rough lumber into shooks of different standard widths that they be sufficiently wider than the standard size to allow for a final trimming of the edge or edges thereof without reducing the said board or shook below the said standard widths, for example to allow for the final trimming, the board should be cut about $\frac{1}{8}$ " wider than the standard width.

My present invention, which is especially designed for applying a final edge trimming

to box shooks, is more particularly provided for applying to the well known types of rotary disk jointers, an improved means for supporting the shooks and feeding them edgewise up against the rotary planing disk and by which the operator, without any special consideration of the particular width of the shook handled, can quickly and accurately adjust the feed of the shook, and in which the final feed adjustment is determined by the condition of the board edge being trimmed, visual to the operator as he observes the trimming operation, or in other words, should the edge of the board show defective portions, requiring more than the extra $\frac{1}{8}$ " surplus or defective edge, the operator can set certain rack and latch devices for effecting the desired predetermined forward feed of the shook to the cutting disk, so as to provide for removing the initial $\frac{1}{8}$ ", $\frac{1}{4}$ " or more of the edge being trimmed, no matter how serious the defect of that edge being trimmed, whereby to leave the remaining portion of the shook reduced to a standard width.

Another object of my invention is to provide a shiftable holder or table attachment for standard types of disk jointers of a simple and inexpensive character and which includes ratchet and latch devices controlled by the hand that actuates the feed of the table on which the shook is held, for governing the final feed movement of the shook edge to the planer disk and governed by the defective character of the edge being trimmed.

Again, my present invention provides an improved means that is especially designed for the purpose of jointing irregular and defective edges of box shooks to a graduated width, finished in $1\frac{1}{4}$ " or (in any other desired widths of graduation) accurately, the maximum value of the shook.

In the manufacture of box shooks, the character of the lumber, at times, is such that the shooks are cut on a bias and my present invention also has for its purpose to provide among other elements an improved means for holding and feeding shooks of the character mentioned to the planing disk for conveniently and accurately trimming the bias edges of the said shapes of shooks to graduated widths.

With other objects in view and hereinafter explained, my improved box shook edge trimming mechanism embodies the peculiar features of construction and novel arrangement of the parts specifically pointed out in the appended claims and illustrated in the accompanying drawings, in which:

Figure 1 is a perspective view of a duplex type of box shook edge trimming machine constructed in accordance with my invention.

Fig. 2 is a front view of my invention, so much of a jointing disk planer being shown as is necessary to illustrate a practical application of my said invention.

Fig. 3 is a top plan view of the parts shown in Fig. 2 the slidable shook holder being shown with its projecting face parallel with the edge trimmer disk in full lines and in dotted lines, in position for advancing boards having a biased edge.

Fig. 4 is a view similar to Fig. 3 and shows the parts adjusted for trimming the board having a bias edge on a taper reversed to that shown in dotted lines in Fig. 3.

Fig. 5 is a cross section on the line 5—5 on Fig. 3, looking in the direction of the arrow *a*, the board being shown in position for being edge trimmed.

Fig. 6 is a detail perspective view of the shook holder or pusher frame, the parts being separated.

Fig. 7 is a diagram of a shook having a defective edge.

Fig. 8 illustrates the same board trimmed to a point selected by the operator for governing the time when to throw into action the stop latch for finishing the board edge to the next standard width.

Fig. 9 is a detail cross section of a defective edge shook and illustrates how such an edge is fed up to be trimmed to obtain the maximum value of the shook.

Fig. 10 is a diagram of a shook or board of standard width, the dotted lines *a* indicating the primary amount of edge to be trimmed and the dotted line *b* the secondary or final trim to reduce the board to a next standard width.

Fig. 11 is a detail view hereinafter referred to.

As it is usual to build jointer machines with a cutting disk at each end of a driven shaft, and to provide co-operative board holding means for each cutting disk, I have illustrated my invention as applied to each of the oppositely disposed cutting disks, as shown in Fig. 1, it being understood, however, that the following detail description of the operating parts generally applies to the board edge trimming mechanism at one side only.

In the drawings, 1 designates the main framing of a disk jointer, in the oppositely disposed uprights 2 of which is journaled the horizontal shaft 3, which, at each end car-

ries a rotary disk cutter 4, the said cutters being located outside of the dust and shavings blower casings 5—5; the said parts being of a well known construction, form *per se*, no part of my invention.

7—7 designate a pair of oppositely disposed brackets bolted to the main frame and which project outwardly at right angles to the cutting disk.

A bed frame 6 that extends across the face 75 of the cutter disk is mounted on the brackets 7—7 and the said frame includes inner and outer parallel longitudinal bars 60—60 bolted to the brackets 7—7 and cross bars 61—61 bolted to the bar 60, as shown.

By referring to Fig. 3 of the drawing, it will be seen that the innermost bar 60 is positioned closely to the cutting disk and forms, as it were, the shaving bar or chip breaker and for holding the board edge to 85 be trimmed down solid against the said bar 60, as it is being fed up to the cutter, vertically adjustable guides 8—8 therefor are attached to the brackets 9—9 mounted one at each end of the said inner bar 60, the said 90 brackets including horizontal arms that have elongated horizontal slots 82 that provide for lateral shifting of the vertically adjustable guides 8—8 before mentioned.

A pair of spaced cross bars 62—63 are 95 mounted on the bars 60—60 midway the length thereof and the said bars 62—63 form a guideway for a slide bar 10 movable to and from the cutter disk in the manner and for the purpose presently explained.

11 designates a board holder or pusher frame and the said frame, in practice, is in the nature of a flat casting formed with an inner vertical edge or fence 12 that is provided at one end with a laterally adjustable stop 13 that forms an abutment for one end of the shook to be trimmed.

Casting 11 is pivotally attached at 14 to the slide bar 10 to swing in the horizontal plane over the frame 6 and the said 110 casting includes a semi-circular outer end provided with a series of annularly arranged notches or apertures 15 for coengaging with a latch pin 16 on an adjusting lever 17 hereinafter again referred to.

As before stated, in the manufacture of standard sizes of shooks, it is essential that their edges be clear of imperfections and that the size be accurate so as to provide for a perfect assembling of the boards when put into box shape and to do this, it is necessary to provide the boards with a surplus width to provide for producing the desired edge finish.

For controlling the edge trimming operation and regulating the edgewise feed of the board or shook, I employ a selective ratchet and pawl mechanism, the construction of which (best shown in Figs. 4 and 5) embodies a ratchet bar 18 that is secured 130

upon the under side of the cross bar 63 with the ratchet facing and in parallelism with the slide bar 10.

In the construction shown, the ratchet 5 teeth are spaced $\frac{1}{8}$ " apart and are so assembled, with respect to the cutting disk, that they form a series of predetermined stops for being engaged by a detent pawl 23 on the lower end of the stem 21 of a 10 hand hold 20 which projects above the pusher casting and which forms the means whereby the slide and the pusher are moved toward and from the disk cutter.

The stem 21 is rotatably mounted in the 15 slide 10 and it also passes through a slot 22 in the pusher that is curved on an arc concentric with the pusher pivot connection, the reason for which will presently appear.

Operation.

Assuming the parts to be in the position shown in Fig. 3 and shook lengths of say 20" long are to be edge trimmed, the stop 13 on one end of the pusher frame 11 is set 25 to receive one end of the shook against it and thereby hold the shook from longitudinal creeping as the edge to be trimmed is being projected to the disk cutter, which is done by the operator grasping the handle 20 and at the same time turning it to bring the latch or detent 23 so it clears the ratchet bar 18 as the board is being fed up to the cutter.

In placing the board in position for being fed to the cutter, the operator observes the condition of the edge to be trimmed and assuming the edge to be trimmed to be "barked" as indicated in Fig. 7, the operator places that face of the board or shook 40 uppermost whose edge shows the least bark or defect, see Fig. 9.

If the board to be trimmed be $4\frac{3}{8}$ " wide or less than $\frac{1}{8}$ " wider than the standard width of $4\frac{1}{4}$ ", the operator as he grasps the handle 20 to advance the slide 10, at the same time turns the said handle to bring the pawl 23 into engagement with the selective ratchet bar, it being understood that no matter at which point between any adjacent pair of 45 stop edges (ratchet teeth) the pawl engages, the pusher bar will have a forward movement only to that portion or ends of the $\frac{1}{8}$ " distance that the pawl can go to meet the next stop, or in other words, stop action 50 on the pusher frame applies only after the said pusher frame has been advanced to the extent of $\frac{1}{8}$ " assuming the ratchet teeth are formed on "eighths". Thus when these selective devices are arranged as shown, the 55 primary trim of the edge being engaged is never more than $\frac{1}{8}$ ".

When the edge to be trimmed is defective to an extent greater than the line of primary trim ($\frac{1}{8}$ "), see α on Fig. 8, the operator places the board with the defective 60

edge in the position the same as a perfect edge board is placed and as he grasps the handle 20 to advance the board, he turns the said handle to release the pawl from the ratchet bar and holds it free until he notices 70 that the board being trimmed has about reached the limit of the maximum line of deflection, see γ Fig. 8, and as he thus notices the board, he turns the handle to bring the pawl 23 to engage with stop ratchet 75 that may be in line with the pawl, the latter traveling as the handle and slide are pushed forward the final distance of the stop ratchet with which it engages and thereby effects the secondary trim of $\frac{1}{8}$ ". 80 Thus a defective edge board originally cut for a standard width of $4\frac{1}{4}$ " is edge trimmed clear of defects down to the next standard size of $4\frac{1}{8}$ ".

It should be stated that in trimming the 85 defective board edge, the defective edge is trimmed down to the standard width measured on the upper surface since a bark edge on the under or inner face is ordinarily of no consequence as that edge is placed on 90 the inside when two boards are edgewise matched and held to be stapled to form a box side, end or top, see Fig. 11.

In handling box shooks, the character of the board, owing to bark edges or knots, is 95 often such that to get the full value of the shook, it must be ripped up into a bias shape, it being understood that when cut bias, two boards of like angle (the bias edges) are matched up to form a box side, 100 end or top.

In my invention, I have provided for trimming the bias or tapered edge of the boards so the said tapered edge may be planed along predetermined lines, or in 105 other words, the said bias edge is held in parallelism with and advanced to the cutter disks the same as is done with a straight edge board.

For such purpose, the adjusting lever 17 110 before referred to has a fixed fulcrum 25 on the pusher 11 and also has a slidable fulcrum pin 26 that works through a segmental slot 27 in the pusher 11, curved about the fulcrum 25 and which slidably engages a 115 longitudinally elongated slot 28 in the slide 10, as shown.

By reason of connecting the lever 17 to coöperate with the pusher 11 and the slide 10, as shown, the operator can quickly adjust the pusher frame with its front or fence edge at any desired angle with respect to the face of the cutter disk for advancing the bias or tapered board, as indicated in Figs. 3 and 4.

It should be here stated that in my construction of shook edge trimmer, the cutter disk is held in a relatively fixed position with respect to the pusher or fence and is not in any way changed or shifted for trim- 125 130

ming the bevel or bias edges, since in my construction of parts, the bias or tapered edge is as a straight edge that is fed up to and is adapted for being trimmed down to

5 produce the selective trim graduations the same as is done to a shook having parallel opposite edges.

One of the advantages in taking care of defective edge boards or shooks in the manner shown and described is that it saves the time in throwing aside a defective board and handling it again for a resaw to reduce it to a lower standard width.

My method of handling and trimming box shooks saves assorting the different widths, facilitates the trimming operation and avoids the use of more or less complicated mechanism necessary when edge trimming with a matcher head cutter or planer.

20 In the use of my invention no skill is required of the operator, since no special selection of the shooks that are furnished him is required and no setting or adjusting of parts for controlling the selected points at 25 which the advance of the board to the cutter should stop.

In taking up the shook, the operator places the defective edge on the pusher frame, with the maximum defective portion at the 30 bottom and in grasping the handle 20 gives it a turn to swing the pawl 23 out of the rack, the handle being thus held while the operator advances the slide and the pusher together with the board to the cutter, which 35 movement continues until the operator notices that the defective edge is nearly trimmed to the minimum degree. The handle 20 is then turned in the other direction to bring the pawl against the stop ratchet 40 as the pushing of the board is still continued; it being understood that so soon as the pawl engages the ratchet, the feed movement is limited to the distance the pawl edge travels along the ratchet tooth and until it 45 engages the next tooth or stop.

What I claim is:

1. In a board edge trimming machine, the combination with an edge planer; of means for holding the board to be trimmed at right angles to the planer and for pushing the board toward the planer with the edge to be trimmed in a plane parallel with the planer, a selective stop device including a ratchet and a manually shiftable pawl, the latter being adapted for being moved into engagement with the ratchet at such predetermined times as the condition of the edge of the board being trimmed may indicate, whereby to leave the remainder of the board of a 60 standard width.

2. The combination with a board edge planer; of a slide member for pushing the board edgewise against the planer, a handle by which the slide member is pushed forwardly and a selective stop device coöpera-

tive with the said handle, adapted to be brought into operative condition at times determined by the defective condition of the board edge as it is being trimmed.

3. The combination with a planer, the 70 table and the board feeding slide; of a selective stop device for arresting the forward movement of the slide and a device by which, when applied in one direction, the slide is moved to feed the board and when 75 applied in another direction, the selective stop device operates to arrest the said forward movement of the slide.

4. The combination with a planer, the 80 table and the board feeding slide, a selective stop device for arresting the forward movements of the slide and a member coöperative with the slide and the selective stop device and adapted for substantially simultaneously advancing the slide and setting the 85 stop device.

5. In a box shook edge trimming machine, an edge trimming cutter, means for holding the board to be edge trimmed and advancing it to the cutter, the said means including a 90 board pusher having a fence edge and devices for adjusting the pusher to bring the fence edge at different angles whereby to set straight edges or bias edges of the board to be trimmed in parallelism with the cutter as 95 the board is being trimmed.

6. The combination with a cutter; of a slide member movable in a plane at right angles to the cutter, a pusher frame pivotally mounted on the slide member for adjustment laterally with respect to the slide and in the horizontal plane, a handle by which the slide and pusher are advanced, and a selective stop device coöperative with the said handle for arresting the movement 100 of the slide member and the pusher.

7. The combination with a cutter; of a slide member movable in a plane at right angles to the cutter, a pusher frame pivotally mounted on the slide member for adjustment laterally with respect to the slide and in the horizontal plane, a handle by which the slide and pusher are advanced and a selective stop device coöperative with the said handle for arresting the movement of 115 the slide member and the pusher, means mounted on the pusher and coöperative with the slide for shifting and holding the said pusher to different lateral adjustments, whereby to present the board engaging face 120 of the pusher at different angles with respect to the cutter.

8. The combination with a cutter; of a slide member movable in a plane at right angles to the cutter, a pusher frame pivotally mounted on the slide member for adjustment laterally with respect to the slide and in the horizontal plane, a handle by which the slide and pusher are advanced and a selective device coöperative with the said 125 130

- handle for directing the movement of the slide member and the pusher, means mounted on the pusher and coöperative with the slide for shifting and holding the said 5 pusher to different lateral adjustments, whereby to present the board engaging face of the pusher at different angles with respect to the cutter, said means including a detent, a lever that carries the detent having a fixed 10 fulcrum on the pusher frame and a slidable fulcrum connection with the slide, the said pusher frame having annularly arranged detent locking portions.
9. In a board edge trimming mechanism, 15 a rotary cutter disk, means for holding the board to be edge trimmed at right angles to the disk, the said means including inner and outer longitudinal bars, the inner one being held close to the cutter disk, transverse bars 20 that connect the longitudinal bars, two of the said transverse bars forming a trans-
verse slot and means on the innermost longitudinal bar for holding the board being passed to the cutter down to the cutter engaging position, a slide operable in the 25 transverse guide slot, a board pusher pivotally connected to the slide and means that provide for predetermined graduated feed movements of the slide and the pusher.
10. In a mechanism of the character stated, 30 a rotary cutter disk, means for holding the board to be trimmed at right angles to the disk, means for gradually advancing the board edgewise toward the disk, further means for determining the time operations 35 of the said board advancing means including a rotatable hand hold and a detent on the hand hold that coöperates with the means for determining the time operations of the board advancing mechanism.
